UNITED STATES PATENT OFFICE.

AUGUSTO RODAL, OF HABANA, CUBA.

TOOTH-PICK HOLDER.

1,243,344.

Specification of Letters Patent. Patented Oct. 16, 1917.

Application filed August 16, 1916. Serial No. 115,194.

To all whom it may concern:

Be it known that I, AUGUSTO RODAL, a citizen of the Republic of Cuba, and a resident of Habana, Cuba, have invented certain new and useful Improvements in Tooth-Pick Holders, of which the following is a specification.

The invention relates to tooth-pick holders used for table ware and its object being to provide a tooth-pick holder capable of furnishing a tooth-pick without drawing one out with the fingers, but by means of discharging mechanism which is properly actuated, thus providing a device having important sanitary advantages.

The invention is described with reference to the figures of the annexed drawings in which:

Figure 1 is a top plan view of a tooth-pick holder, constructed according to my invention.

Fig. 2 is an end elevation of the tooth-pick holder, shown in Fig. 1.

Fig. 3 is a front elevation of same.

Fig. 4 is a vertical longitudinal section of the said tooth-pick holder through the central part of same.

Fig. 5 is a vertical transverse section of the said tooth-pick holder.

Fig. 6 is an end elevation of same, and an end cheek being taken off to show the tooth-pick discharging mechanism.

Fig. 7 is a detail view in perspective showing the lower shifting cover which forms a part of the tooth-pick discharging mechanism.

This tooth-pick holder is composed of a horizontal cylinder 1 which forms the receptacle for the tooth-picks 2. Said cylinder has in its lower part an aperture 3 of greater length than that of the tooth-pick and whose lateral edges 4 are bent downwardly, and said cylinder has also a longitudinal aperture 5 in its upper part, said cylinder is closed near its ends by means of vertical plates 6 beyond which the cylinder projects outwardly forming annular flanges 1' broken away at the lower part of the cylinder, and said cylinder 1 is supported by

means of the end cheek 7 which are of circular shape in their upper part and in the lower part they are widened so as to form bases 7' to bear on the horizontal table or other support and each one of the cheeks 55 has an inner flange 7''. The cheeks may be adjusted on the flanges 1' of the cylinder

1, the flanges 7'' being secured to the flanges 1' by means of small screws 8, one at each side; the plate of each cheek 7 being at a certain distance from each vertical plate 60 or end wall 6 of cylinder 1. The upper longitudinal aperture 5 of cylinder 1 is closed by means of a plate 9 having a transverse cross-section in the form of an arc and which is slidable along said aperture 65 and fits on the edges thereof by means of lateral flanges 10 which project therefrom. At one end said plate 9 is provided with an upper projection 11 from which extensions 12' extend to the sides and are superposed to the longitudinal edges of the aperture 5 and by means of which plate 9 is supported from the edges of said aperture, 70 said edges serving as a guide to the plate 9 in its sliding movement. This plate 9 has 75 on its other end a small handle 12 to move the same inwardly or outwardly. The lower longitudinal aperture 3 of the cylinder serves for the discharge of the tooth-pick and it is closed below by means of a shifting cover consisting of a plate 13 of arched 80 or circular form in transverse cross-section and having its edges 13' raised until nearly touching the outer surface of cylinder 1. Said plate 13 has in its center an aperture 85 14 of greater length than that of a tooth-pick and whose edges 15 are bent downwardly, the width of said aperture 14 being hardly larger than that of a tooth-pick in order that only one tooth-pick at a time may 90 be able to pass through said aperture. This plate 13 is rigidly connected at its ends to two suspension arms 16 which are rotatively mounted on journals 16' projecting from the center of the vertical plates 6. 95 Said arms 16 lie intermediate the ends of the cylinder 1 and the cheeks 7 outside of the plate 6 at the end of the cylinder. Underneath said plate 13 there is supported a small longitudinal plate 18 of slightly 100 arched transverse cross section which closes the aperture 14, formed in the center of the plate 13 when the plate 13 is in its normal central position.

The means employed to move the plate 105 13 with its two arms 16 on the journals 16' consists of an upwardly directed angular extension 19 formed on one of the arms 16 and which has on its upper end a small handle 20, the stem 20' of which projects outwardly through an opening 21 formed on one of the flanges 1' of the cylinder 1 and

7" of one of the cheeks 7, a spring 22 being wound on journal 16' which is attached by one of its ends to a small clamp 23 fixed on the outer face of end wall 6 of cylinder 1. 5 By its other end said spring 22 is attached to a small clamp 24 fixed on the outer face of the corresponding arm 16. By means of this arrangement, each time that the arms 16 together with the discharging plate 10 13 are displaced from their normal position by operating the small handle 20, said spring 22 returns the same to their normal position by virtue of the elastic tension exerted by the spring as soon as the handle is 15 released.

In the base 7' of each cheek there is rigidly fixed a wire member 25 of downwardly curved form which is arranged in transverse position with its ends angularly bent 20 and which forms a support for receiving the ends of the tooth-pick 2 that fall from the receptacle 1 when the discharging mechanism is properly actuated.

The operation of the apparatus is as follows:

Supposing cylinder 1 is occupied by a certain number of tooth-picks and the plate 13 with arms 16, is in the position shown by full lines in Figs. 4 and 6 of the drawings, that is the aperture 14 of the plate 13 being closed by the lower fixed plate 18, the small handle 20 is pulled by the fingers to the front and downwardly to shift backward arms 16 and plate 13 against the elastic tension of spring 22, whereupon, as the aperture 14 passes beyond the rear edge of the small obturating plate 18, the tooth-pick that was occupying the space of said aperture 14 falls down, it then being caught and 40 held in the lower supports 25. At the time of letting loose the small handle 20, the arms 16, with the lower plate 13, turn back again to their normal position until aperture 14 is again obturated by the small plate 45 18, another tooth-pick falling into said aperture 14 which also is discharged when the discharging mechanism is operated once more by means of small handle 20.

It is obvious that the form of the cylinder 50 and that of the cheeks 7 as well as that of plates 13 and 18 may be changed without altering the spirit of the invention, which is as pointed out in the appended claims.

Having thus described my invention I 55 claim:

1. In a tooth-pick holder, the combination with a cylindrical receptacle provided with a lower discharging aperture, said receptacle having end walls, flanges on said end 60 walls, a shifting cover below said lower aperture provided with a longitudinal aperture to afford a passage for just one tooth pick, a fixed plate normally obturating said longitudinal aperture of said cover of a 65 pair of cheeks supporting the ends of said

receptacle and whose upper portions are spaced outwardly from the end walls of said receptacle, flanges on said cheeks which are adjustable on said receptacle flanges, means for securing said cheek plates to said 70 receptacle flanges, and suspension means for said shifting cover which projects upwardly between each end wall of the receptacle and the corresponding spaced cheek, journals projecting from said end walls, said means 75 being pivotally mounted on said journals, a portion of said means projecting outwardly from one of said suspension arms for rotating said cover in its journals, and a spring for resisting the movement of said 80 cover away from the position of obturation.

2. In a tooth-pick holder, the combination with a cylindrical receptacle provided with a lower discharging aperture and having end walls, flanges on said receptacle, a shifting cover below said aperture provided with a longitudinal aperture to afford passage for just one tooth pick, and an immovable plate normally obturating said longitudinal aperture of said cover, of a pair of 90 cheeks supporting the ends of said receptacle and whose upper portions are spaced from the end walls of the receptacle, flanges on said cheeks which fit on the flanges on the receptacle, means for securing the cheek 95 flanges on said receptacle flanges, suspension arms for said shifting cover which project upwardly between said end walls of the receptacle and said spaced cheeks, journals on said end walls in which said suspension arms are supported, one of said shifting cover suspension arms being provided with an extension projecting outwardly and ending in a handle, and a pair of arched members projecting from the 100 cheeks beneath the discharging aperture for receiving the ends of every falling toothpick.

3. In a tooth pick holder, the combination with a cylindrical receptacle provided with a lower discharging aperture, said receptacle having end walls, flanges on said end walls, a shifting cover below said lower aperture and provided with a longitudinal aperture to afford a passage for just one tooth pick, a fixed plate normally obturating said longitudinal aperture of said cover, of a pair of cheeks supporting the ends of said receptacle and whose upper portions are spaced outwardly from the end walls of said receptacle, flanges on said cheeks which are adjustable on said receptacle flanges, means for securing said cheek plates on said 115 end flanges in adjusted relation, suspension arms for said shifting cover which project upwardly between each end wall of the receptacle and the corresponding spaced cheek, journals projecting from said end walls, said suspension arms being pivotally 120 mounted on said journals, means projecting 125

130

outwardly from one of said suspension arms for rotating said cover on its journals, and a spring for resisting the movement of said cover away from the position of obturation.

5 4. In a tooth pick holder, the combination with a cylindrical receptacle provided with a lower discharging aperture and having end walls, flanges on said receptacle, a shifting cover below said aperture and provided with a longitudinal aperture to afford 10 passage for just one tooth pick, and an unmovable plate normally obturating said longitudinal aperture of said cover, of a pair of cheeks supporting the ends of said receptacle and whose upper portions are spaced 15 from the end walls of the receptacle, flanges on said cheeks which fit on the flanges on the receptacle, means for securing the cheek flanges on said receptacle flanges, suspension 20 arms for said shifting cover which project

upwardly between each end wall of the receptacle and the corresponding spaced cheek, said end walls having journals projecting therefrom on which said suspension arms are pivotally mounted, a spring wound in one of 25 said journals and having one of its ends fixed to the respective end wall and the other of its ends fixed to the respective suspension arm, this shifting cover suspension arm being provided with an extension projecting outwardly and ending in a handle, and a pair of arched members projecting from the cheeks beneath the discharging aperture for receiving the ends of every falling tooth pick. 30

In testimony whereof I affix my signature 35 in presence of two witnesses.

AUGUSTO RODAL.
